UNITED STATES PATENT OFFICE.

ALONZO L. EDWARDS, OF WHEELING, WEST VIRGINIA, ASSIGNOR, BY DIRECT AND MESNE ASSIGNMENTS, TO IRWIN PAUL, TRUSTEE, OF WHEELING, WEST VIRGINIA.

LANTERN-FRAME AND BLANK FOR MAKING SAME.

SPECIFICATION forming part of Letters Patent No. 732,529, dated June 30, 1903.

Application filed March 27, 1903. Serial No. 149,788. (No model.)

To all whom it may concern:

Be it known that I, ALONZO L. EDWARDS, of Wheeling, Ohio county, West Virginia, have invented a new and useful Lantern-Frame and Blanks for Making Same, of which the following is a full, clear, and exact description, reference being had to the accompanying drawings, forming part of this specification, in which—

10 Figure 1 is a plan view showing one of the blanks after the first step of drawing. Fig. 2 is a cross-section on the line II II of Fig. 1. Fig. 3 is a plan view showing the blanks after the second drawing operation. Fig. 4 is a cross-section on the line IV IV of Fig. 3. Fig. 15 5 is a plan view of the blank after trimming. Fig. 6 is a cross-section on the line VI VI of Fig. 5. Fig. 7 is a plan view of the tubular frame, and Fig. 8 is a cross-section on the line 20 20 VIII VIII of Fig. 7.

My invention relates to the class of tubular lantern-frames wherein the side tubes are connected at the top with a central depending draft-tube, and it is designed to reduce the 25 number of blanks, the number of drawing operations, and the work of assembling and securing the parts, and at the same time produce an article which is free from soldered joints in the upper portion of the frame and is more 30 attractive in appearance than previous lanterns of this type.

In carrying out my invention I form the entire tubular frame from two similar blanks or halves which are seamed together, and in 35 shaping these blanks I cut from a metal sheet a blank of proper size and shape, similar to that of Fig. 1, with excess metal in the lower inner corners 22 and with two lobes 33 cut in each upper portion at the sides of the draft-tube portion. These lobes, however, leave 40 excess metal between them and the top portion of the blank. This blank is then drawn up into the form of Fig. 1, in which the half-tube is partially formed, the lower elbow portions 44 being connected by the continuous 45 lower web of metal 5. This cutting of the blank with the web connecting the lower elbows is of great advantage in drawing, for it holds the separated legs together, enables the 50 blank to be handled more easily, and prevents

drawing in of the legs toward each other during the drawing operation. It is well known to those skilled in this art that in the drawing up of such blanks there is a strong tendency to draw the legs toward each other, and thus 55 distort the blank, especially where the central draft-tube is drawn up at the same time. This tendency is overcome by providing the connecting - web between the lower elbow portions, since this web holds the legs apart 60 and keeps them in proper relative position during the drawing. My broader claims are not limited to the use of this connecting-web; but I claim the same specifically, as it affords a cheap and simple means for holding 65 the legs in proper position. In the first drawing operation I preferably also cut the blank from the sheet, the inner part of the blank having been previously cut out, though this may or may not be done, as desired. After 70 the first drawing operation I preferably cut away the metal above the upper lobe portions, as shown at 66 in Fig. 3, thus removing part of the metal which has been injured in the first step of drawing, and avoiding tearing or 75 drawing of the injured portion into the blank proper. This step of cutting away I have found important in preventing cracks at the corners of the tube. After this cutting out the blank is subjected to the second drawing 80 operation, in which operation the blank is completely formed, including the semicylindrical draft-tube 7, as shown in Figs. 3 and 4. The side legs and elbow portions are preferably completely formed at the first drawing 85 operation. After the second drawing operation the blank is trimmed to make the flanges or seaming portions of a uniform width, as shown in Fig. 5, one blank being trimmed slightly wider than the other to give the overlapping portion of the seam. The connecting-web portion 5 is then cut out, leaving the elbow portions 4 with a gap between them, and the blanks are then seamed together, forming the tubular frame of Figs. 7 and 8. 90 The lower elbows 4 are preferably soldered into the bowl of the lantern, no solder being used in the other parts of the seams, and these soldered joints, with the bowl, make the frame rigid and prevent movement in the seams. 95 100

The advantages of my invention result from the small number of drawing operations and of blanks and the use of the connecting-web at the bottom, which holds the legs together and in proper relative position. The frame thus formed is free from transverse joints in its upper parts, and hence is longer lived and more attractive in appearance than former constructions.

10 The providing of excess metal above the lobes at the top and the cutting away of part of this metal after the first drawing prevents cracking and carrying of the blank.

15 Many changes may be made in the shape and size of the blanks, the steps employed in forming them, the manner of seaming, &c., without departing from my invention.

I claim—

1. The method of drawing a tubular lantern-blank having side tube portions integrally united at the top and provided with an integral central tube portion, consisting in cutting out the interior of the blank with side lobes, subjecting the blank to the drawing operation, cutting said lobes upwardly, and then subjecting the blank to the further drawing operation; substantially as described.

2. The method of forming a tubular lantern-blank, with an integral central tube portion, consisting in cutting out the inner portion of a blank, leaving continuous side portions united at the top and provided with a central depending portion at said top, and with lower elbows, drawing said blank, cutting away portions of metal on each side of the central tube portion, subjecting the blank to a further drawing operation, and then trimming the blank; substantially as described.

3. The method of drawing a tubular lantern-blank with an integral central tube portion, consisting in cutting out the inner portion of a blank, leaving the side leg portions integrally united at the top and provided with a depending central tube portion, the side leg

45 portions having lower elbows united by a con-

necting-web, drawing the blank, and then cutting away the connecting-web between the lower elbows; substantially as described.

4. A tubular lantern-blank having side tube portions with lower integral elbow portions, the side tube portions being integrally united at the top, and provided with an integral depending central-draft-tube portion; substantially as described.

5. A lantern-blank having tubular side portions integrally united at the top, and having integral lower elbow portions, said side portions being provided with an integral depending central-draft-tube portion; substantially as described.

6. A tubular lantern-blank having tubular side portions integrally united at the top and provided with an integral depending central-draft-tube portion, said side tube portions having lower integral elbow portions held by an integral connecting-web extending between them; substantially as described.

7. A tubular lantern-blank having side tube portions provided with lower inwardly-projecting integral elbow portions with their inner ends separated from each other, said side tube portions being integrally united at the top and provided with an integral depending central-draft-tube portion; substantially as described.

8. A tubular lantern-frame composed of two similar blanks seamed together at their edges, each blank having tubular side portions integrally united at the top and provided with an integral depending draft-tube portion, said side portions having integral lower elbow portions with their inner ends cut apart and separated from each other; substantially as described.

In testimony whereof I have hereunto set my hand.

ALONZO L. EDWARDS.
